LIGHTING FIXTURE

Edward F. Zurawski and Frank Schram, Chicago, Ill., assignors to Garey Corporation, a corporation of Illinois

Filed Jan. 24, 1963, Ser. No. 253,664

5 Claims. (Cl. 248—343)

This invention relates to a lighting fixture, and is particularly concerned with a fixture having an outer frame that is installed as a unit in an opening in the ceiling during the regular construction of a building, and a reflector that is installed as a unit in the outer frame after the construction work is finished and the interior of the building is clean.

Both sides of the outer frame are provided with a bracket near each end of the frame for mounting the outer frame in an opening provided therefor in the ceiling. The brackets are held in retracted position by latches each of which has a lip projecting outwardly from its lower end. When the outer frame is pushed upwardly into the opening in the ceiling, the outwardly projecting lips engage the edges of the ceiling defining the opening and release the latches automatically. The brackets are spring pressed and move outwardly, upon release of the latches, to engage the beams or support members mounted on top of the ceiling. The support members are made in different configurations by different manufacturers of building hardware, and the lower edge of the brackets may be shaped to fit any specific support.

After the outer frame is in position, with the brackets resting on the top surface of the beams or similar support members, it is tightened into its final position by means of adjusting screws that are accessible from below the frame. In the final position of the outer frame its bottom surface is preferably approximately flush with the lower surface of the ceiling. The outer frame has a slot at each end. The heating and ventilating contractor can work through the opening in the outer frame to place an air diffuser box over each of the slots at opposite ends of the outer frame. One diffuser box is connected to a cold air duct to transmit cold air to the room in which the fixture is installed. The cold air diffuser box is provided with fiber glass insulation on the side opposite the intake so that the cold air doesn't get warmed by the warm air in the plenum. The other slot allows the warm air to flow from the room in which the fixture is installed to the plenum. The diffuser box mounted above the warm air slot limits the amount of warm air that is returned to the plenum and also helps to insulate the fixture against transmission of sound.

The outer frame of the fixture is also provided with an electrical socket that is wired to a circuit provided therefor. When the reflector is mounted in the outer frame it is hinged on the side of the outer frame having the electrical socket so that it can swing pivotally about said one side, and is latched to the opposite side of the outer frame. The outer frame is provided on three of its edges with a gasket of foamed polyethylene, rubber, or any other suitable material to prevent transmission of sound when the fixture is closed. The hinged side of the reflector is provided with an electrical plug that fits into the socket on the outer frame when the reflector is swung upwardly into its normal position of use. The reflector unit is energized when it is swung upwardly into its normal position of use, and is de-energized when its latch is released and the reflector is swung downwardly about its pivotal connection with the outer frame.

The construction of the outer frame that permits the reflector to be mounted at any time after the outer frame has been secured in place has several advantages. During the construction work the reflector unit may be pro-

2

tected against the dust and dirt incidental to such work. The reflector unit may remain in its protective wrapping until the interior of the building is substantially clean. Then, when the reflector unit is unwrapped and mounted

5 in the outer frame it is clean, and may be used without any extra cleaning job. If the reflector is mounted in the outer frame at the time the outer frame is secured to the ceiling, subsequent dirt from the construction work would make it necessary to clean the reflector before it could be used.

The structure of the present invention has another advantage in that it enables the contractor to save expense during the construction of a building. In building practices heretofore used, the unions have insisted that a member of the heating and ventilating workers union install the air diffuser boxes on the fixture. Then, after installation of the fixture by a member of the electrical workers union, a member of the heating and ventilating workers union was required to connect the cold air diffuser box to the cold air duct. In the installation of a fixture constructed in accordance with the present invention, the diffuser boxes are not installed on the fixture until the outer frame of the fixture is mounted in the ceiling. When the cold air diffuser box is installed on the outer frame of the fixture it may be connected to the cold air duct by the same workman as an additional step in the same operation.

For maintenance, the reflector may be removed from the outer frame as a unit and replaced with a reflector unit in good condition. The replaced reflector unit may then be serviced or repaired at the leisure of the maintenance man. Thus, when a light goes out, persons working in the room don't have to wait while the maintenance man determines whether the bulb has burned out or whether the trouble is somewhere else. The removal of the reflector unit also provides access to the plenum for the wiring or for any other purpose. A reflector unit may also be removed for replacement by a reflector unit having a different number of bulbs therein.

Suitable structure by means of which the above mentioned and other advantages may be attained will be fully described in the following specification, taken in conjunction with the accompanying drawings showing a preferred embodiment of the invention, in which:

FIGURE 1 is a bottom plan view of a fixture embodying the invention as it is installed in the ceiling of a room;

FIG. 2 is a fragmentary perspective view of the outer frame ready for movement upwardly through an opening in the ceiling;

FIG. 3 is a diagrammatic side elevational view showing the outer frame as it is moving upwardly into the opening before the latches holding the mounting brackets have been released;

FIG. 4 is a view, similar to FIG. 3, immediately after release of the bracket holding latches;

FIG. 5 is a view similar to FIG. 4, after the outer frame is lowered to cause the mounting brackets to rest on the supporting members;

FIG. 6 is a view similar to FIG. 3, after the adjusting screws have been tightened to secure the outer frame against the ceiling;

FIG. 7 is an enlarged fragmentary cross sectional view showing the latched side of the reflector secured to the outer frame, and one mounting bracket seated on a beam;

FIG. 8 is a view similar to FIG. 7, but showing the hinged side of the reflector secured to the outer frame;

FIG. 9 is a fragmentary detail sectional view showing the adjusting screw and the spring pressed inner end of the mounting bracket;

FIG. 10 is a cross sectional view, taken along the line 10—10 of FIG. 9;

FIG. 11 is an enlarged longitudinal sectional view, taken along the line 11—11 of FIG. 1;

FIG. 12 is an enlarged fragmentary cross sectional view, taken along the line 12—12 of FIG. 11;

FIG. 13 is a cross sectional view, taken along the line 13—13 of FIG. 7, showing the mounting bracket in its latched position in dot and dash lines;

FIG. 14 is a fragmentary side elevational view, showing one form of mounting bracket in latched position against the side of the outer frame;

FIG. 15 is a view, similar to FIG. 14, showing a different form of mounting bracket;

FIG. 16 is a fragmentary end view, partly in elevation and partly in section, showing the mounting bracket supported on one form of supporting member; and

FIG. 17 is a view, similar to FIG. 16, showing the mounting bracket supported on a different form of supporting member.

Referring to the drawings, the lighting fixture comprises an outer frame 2, and a reflector 3 detachably pivoted to the outer frame. A diffuser panel 4 may be secured to the fixture in any suitable manner. The outer frame is mounted within an opening 5 provided therefor in a ceiling 6. The ceiling may be of any suitable construction, but for illustrative purposes has been shown as having hangers 7 depending therefrom to support panels 8 of a drop ceiling. A plurality of beams 9 extend along the top of ceiling 6 to support the outer frame. Mounting brackets 10 extend outwardly from the outer frame, as hereinafter described, to engage the upper surface of beams 9 and thereby support the outer frame. The outer frame also has a base 11 in the form of a hollow flat rectangle. The outer edges of base 11 are bent upwardly to form flanges 12 adapted to engage the bottom surface of panels 8 when the outer frame is in place.

A housing 13 is mounted on base 11 near each end of the outer frame. Each housing 13 has two relatively short side walls 14 and 15 supported on base 11 and connected by an end wall 16 integral therewith. The upper edge of end wall 16 is bent over to form a top flange 17 approximately flush with the upper edges of side walls 14 and 15. The lower edge of end wall 16 is bent at right angles in the opposite direction to form a flange 18 that terminates in spaced relationship to the inner edge of base 11 to form a slot 19. A similar slot 20 is formed at the opposite end of the outer frame by identical structure. At each end of the outer frame an L-shaped member 21 has a horizontal leg 22 welded to base 11 and a vertical leg 23 extending upwardly therefrom. Vertical leg 23 comprises an end section 24 and two side sections 25 extending from the outer ends of section 24 to end wall 16 of housing 13. Vertical leg 23 cooperates with end wall 16 to form an open top enclosure surrounding slot 19, and a similar enclosure surrounds slot 20 at the opposite end of the outer frame. End section 25 of each vertical leg 23 abuts the edge of adjacent panels 8 when the outer frame is mounted in the ceiling.

A longitudinally extending bracket 26 has its opposite ends secured to side walls 14 adjacent opposite ends of the outer frame, and a similar bracket 27 has its opposite ends secured to side walls 15. The upper edge of bracket 26 is bent inwardly to form a horizontal section 28, upwardly to form a vertical section 29, and then inwardly to form another horizontal section 30. Although the bending is described as a step by step operation for the sake of clarity, it will be understood that ordinarily the three bending operations are performed simultaneously. Bracket 27 is similarly bent to form a horizontal section 31, a vertical section 32 and a horizontal section 33.

Mounting brackets 10 adjacent each corner of the outer frame are each mounted in the same manner, so only one will be described. Each mounting bracket 10 comprises a flat section 34 latched in place on the outside of side wall 14 or 15, and another flat section 35 extending at right angles to flat section 34. Side walls 14 and 15 are

each provided with a vertical slot 36 having a length substantially greater than the height of section 35 of supporting bracket 10. Section 35 extends through slot 36, as shown in FIG. 10. As shown best in FIG. 9, a channel 37 extends at right angles to section 35 and is secured to its outer edges.

Channel 37 comprises a web 38 having a centrally disposed opening 39 and a pair of flanges 40 and 41 having aligned openings 42 and 43, respectively. An adjusting screw 44 extends through section 28 of bracket 26, through both openings 43 and 42, and through top flange 17 of housing 13. Screw 44 has a slotted head 45 adjacent the lower surface of section 28. The slotted screw head is accessible from below the outer frame so that if the outer frame does not fit snugly against the ceiling when support brackets 10 rest on beams 9, the screw may be turned to position the outer frame properly.

A square nut 46, threaded on screw 44 between flanges 40 and 41, has one corner 47 extending through opening 39 to prevent vertical movement of the nut when the screw is turned. The screw cannot move channel 37 because of the clearance at both openings 42 and 43. Since nut 46 is fixed in its vertical position, rotation of screw 44 causes the screw to move vertically relative to the nut, and the screw carries outer frame 2 with it. After the outer frame is moved into opening 5, screw 44 is rotated in one direction to move flange 12 into tight engagement with ceiling panel 8.

A torsion spring 48, coiled around screw 44, has one end 49 biased against end wall 16 of housing 13 and its other end 50 biased against the inner surface of web 38 of channel 37. The spring extends through opening 39 in web 38. Since mounting bracket 10 is secured to channel 37, the pressure of spring 48 constantly urges the mounting bracket outwardly from side wall 14 or 15.

Before installation of the outer frame, mounting bracket 10 is held in retracted position against side wall 14 or 15 by a slidable latch bar 51, as shown in FIG. 2. A plurality of oppositely disposed lugs 52 struck out from side wall 14 or 15 fit against opposite edges of latch bar 51 with sufficient friction to hold the latch bar in place. The upper end 53 of the latch bar is offset and overlies the outer end of mounting bracket 10 to hold it in retracted position against side wall 14 or 15 against the action of torsion spring 48. Latch bar 51 is also offset, as indicated at 53' in vertically spaced relationship to upper end 53, so that mounting brackets 10 may be mounted at a lower level, if desired. The lower end of latch bar 51 is bent outwardly at right angles to provide a lip 54 spaced above base 11.

When the outer frame is to be installed, it is held in vertical alignment with an opening 5 in the ceiling and is then pushed upwardly into the opening. As the outer frame is pushed upwardly into opening 5, each lip 54 moves into engagement with the underside of a ceiling panel 8. Continued upward movement of the outer frame causes supporting bracket 10 to move upwardly out of engagement with upper end 53 of latch bar 51. As soon as supporting bracket 10 clears the upper end of latch bar 51, spring 48 moves the supporting bracket rotationally about the screw 44 until it extends outwardly at right angles to its retracted position. The rotational movement of supporting bracket 10 is stopped by engagement of the supporting bracket with one side of slot 36. When the supporting brackets 10 are moved outwardly from their retracted positions they must be high enough for each bracket to clear the beam or other similar member on which it is to be supported. The effective length of latch bar 51 may be varied to release the supporting bracket at any desired position of the outer frame. After the supporting brackets have been moved from their retracted positions, the outer frame is dropped so that the supporting brackets rest on the beams or other supports. The adjusting screws are then tightened to move the outer frame into tight engagement with the ceiling.

As shown in FIG. 7, the lower edge of section 34 is shaped to provide a horizontal portion 55 adapted to rest on a beam having a horizontal top surface. An adjacent portion of the lower edge of section 34 is provided with a recess 56 that adapts the bracket arm to rest on supporting members of various cross sectional shapes. For example, in FIG. 16 the supporting bracket is mounted on a cylindrical pipe 57, and in FIG. 17, the support member 58 has a tapered edge 59 fitting in the semi-circular recess 56. Section 34 also has an aperture 60 so that the outer frame may be supported by wires depending from an upper support. FIG. 15 shows a supporting bracket 61 having a lower edge that is straight except for an offset 62 at its outer edge. The lower edge of the supporting bracket may have any suitable shape to fit any desired support member.

Base 11 of the outer frame has the shape of a hollow rectangle, with a centrally disposed opening having its sides defined by the inner edges of brackets 26 and 27, and its ends defined by housings 13. At each end of outer frame 2 the L-shaped member 21 co-operates with housing 13 to define an open top enclosure that surrounds slot 19 at one end of the outer frame and slot 20 at the other end. After the outer frame is installed in the ceiling opening, an air diffuser box 63 is placed in the enclosure surrounding slot 19, and an air diffuser box 64 is placed in the enclosure surrounding slot 20. Diffuser boxes 63 and 64 may be duplicates, but preferably box 63 is designed to allow warm or exhaust air to flow from the room in which the fixture is installed into the plenum, and box 64 is designed to allow cool air to flow into the room from a cold air duct. Each end of the outer frame is provided with mounting members 21 to hold the diffuser boxes against accidental displacement.

The structure of the outer frame permits a substantial economy in the cost of installing the fixture. Union rules generally permit installation and connection of air diffuser boxes only by workmen who are members of a heating and ventilating union, and installation and connection of the fixture only by workmen who are members of an electrical union. Combination lighting and ventilating fixtures previously installed required a heating and ventilating union worker to install the air diffuser boxes in the fixture prior to installation of the fixture, then installation of the fixture by an electrical union worker, and finally connection of at least one air diffuser box to the air duct after installation of the fixture. With the structure of the present invention, the heating and ventilating union worker does not have to make two separate trips to the job. The centrally disposed opening in the outer frame permits the heating and ventilating union worker to install and connect the air diffuser boxes after the fixture has been installed.

Air diffuser box 63 has a slot 65 that registers with slot 19 when the box is positioned in its enclosure. Diffuser box 64 has a slot 67 that registers with slot 20, and an inlet opening having a flange 68 that fits into a cold air duct 69. Diffuser box 64 preferably has fiber glass or similar insulation (not shown) on the side thereof opposite the inlet to prevent the cold air from being warmed by the warm air in the plenum. Both diffuser boxes help insulate the room against transmission of sound.

Reflector 3 is detachably secured to the outer frame after the outer frame is installed and the interior of the building is substantially clean. The reflector comprises a flat top wall 70 extending substantially the length of the outer frame and two side sections 71 and 72 that extend angularly downwardly. The outer edges of side sections 71 and 72 are bent to form horizontal sections 73 and 74, respectively, and then bent upwardly to form angular flanges 75 and 76, respectively. Channel members 77, secured to top wall 70 adjacent each end of the reflector, support sockets 78 in which fluorescent tubes 79 are mounted. A gasket 80 secured to the upper surface of top wall 70 adjacent each end extends across the top wall,

side section 71 and a portion of horizontal section 73. Gaskets 81 and 82, preferably of the same material as gasket 80, are secured to the upper surfaces of sections 73 and 74 respectively, and extend longitudinally along said sections.

The portions of gaskets 80 above top wall 70 are clamped between it and the top flanges 17 of the adjacent housings 13. The portion of gasket 80 extending over side section 77 is clamped against said side section by means of tongues 83 bent inwardly from each end wall 16, as shown in FIG. 7. Gasket 81 is clamped between sections 30 and 73, and gasket 82 is similarly clamped between sections 33 and 74. When the reflector is mounted in the outer frame, gaskets 80, 81 and 82 co-operate to insulate the fixture against transmission of sound.

A latch 84 is pivotally secured to the under side of section 73, as shown at 85 in FIG. 12, adjacent each end of the reflector. Latch 84 is provided with a finger piece 86 to facilitate rotation. When latch 84 is turned transversely of the fixture it extends through a slot 87 between sections 28 and 29 of bracket 26 to releasably support one side of the reflector.

The opposite side of the reflector is supported by a pair of hinge strips 88. Each hinge strip 88 is an integral member comprising an angularly disposed section 89 and a horizontal section 90 that extends through a slot 91 at the juncture between sections 72 and 74. Flange 76 is also slotted, as indicated at 92, and section 32 is slotted, as indicated at 93, to permit the end 94 to rest on the top surface of section 31. End 94 is offset, as indicated at 95, to provide stability for the hinge. When latch 84 is released and reflector 3 is allowed to swing downwardly about its pivot, offset 95 co-operates with the upstanding portion of section 32 below slot 93 to keep the reflector from sliding out of its pivotal connection.

As shown in FIG. 8, a housing 99 mounted on the inner surface of side wall 15 of one housing 13 on the outer frame has one wall 100 spaced from and inclined at an angle to side wall 15. An electrical socket 96 is mounted within housing 99 but has its outer face projecting through an opening in wall 100. The portion of socket 96 within housing 99 is wired, by means of leads 101 and 102, to a suitable source of electrical current. The outer face of socket 96 is parallel to wall 100. An extension 98 secured to side wall 72 of reflector 3 has one wall 103 spaced from and parallel to wall 100. A plug 97, mounted in extension 98, is wired to the fluorescent tubes 79 and has its outer end projecting through wall 103 in parallel relationship thereto. Plug 97 has prongs (not shown) adapted to fit into recesses provided therefor in the outer face of socket 96 when reflector 3 is swung upwardly into engagement with the outer frame.

When reflector 3 is latched in place in the outer frame, the lighting circuit is energized, and when it is swung downwardly about its pivot, the lighting circuit is de-energized. Thus, the reflector may be removed from the fixture without bothering about the wiring, and anybody swinging the reflector down to replace a fluorescent tube will know that the lighting circuit is de-energized.

Although we have described a preferred embodiment of the invention in considerable detail it will be understood that the description thereof is intended to be illustrative, rather than restrictive, as many details of construction may be modified or changed without departing from the spirit or scope of the invention. Accordingly we do not desire to be restricted to the exact structure described.

We claim:

1. A lighting fixture adapted to be installed in a ceiling, 70 said fixture comprising a base member and a pair of housings forming an outer frame, each of said housings being spaced from the adjacent end of said base member to provide a support for an air diffuser box, an air diffuser box mounted on each of said supports, a plurality of brackets mounted on said outer frame, latch means for

holding said brackets in retracted position against the sides of said outer frame, means for releasing said latch means, and means for moving said brackets outwardly from said retracted position upon release of said latch means, whereby said brackets may engage a support surface spaced outwardly from said outer frame to hold said outer frame against movement downwardly relative to said support surface, said base member having an opening between said housings to provide access to each of said air diffuser boxes after installation of said fixture in a ceiling.

2. A lighting fixture adapted to be installed in a ceiling, said fixture comprising an outer frame, said outer frame including a pair of housings and a base extending longitudinally beyond the remote ends of said housings, an air diffuser box supported on said base outwardly of the remote end of each of said housings, an air flow passageway extending through the bottom of each air diffuser box, a slot in said base in registration with each of said air flow passageways, a plurality of brackets pivotally mounted on said outer frame, latch means for holding said brackets in retracted position against the sides of said outer frame, spring means urging each of said brackets pivotally outwardly from said retracted position, and means for releasing said latch means, whereby said brackets may swing outwardly and engage a support surface spaced outwardly from said outer frame to hold said outer frame against movement downwardly relative to said support surface, said base having an opening between said housings to provide access to each of said air diffuser boxes after installation of said fixture in a ceiling.

3. A lighting fixture comprising an outer frame adapted to be installed in a ceiling, said outer frame having a centrally disposed opening therein, a plurality of brackets mounted on said outer frame, latch means for holding said brackets in retracted position against the sides of said outer frame, means for releasing said latch means, means for moving said brackets outwardly from said retracted position upon release of said latch means, whereby said brackets may engage a support surface spaced outwardly from said outer frame to hold said outer frame against movement downwardly relative to said support surface, said opening providing access through said outer frame, after installation thereof in a ceiling, for workmen to install and connect accessories above the ceiling at either end of said frame, and means integral with said frame for detachably securing a reflector adapted to extend across said opening.

4. In combination with a ceiling, a lighting fixture comprising an outer frame having a lateral flange extending outwardly from each edge of said frame, said ceiling having an opening to receive said frame with said flanges underlying the edges of said ceiling defining said opening, means on said outer frame for clamping it in place with said flanges approximately flush with the lower surface of said ceiling, and means on said outer frame for detachably securing a reflector thereto.

5. In combination with a ceiling, a lighting fixture comprising an outer frame having a lateral flange extending outwardly from each edge of said frame, said ceiling having an opening to receive said frame with said flanges underlying the edges of said ceiling defining said opening, support members secured above said ceiling on opposite sides of said opening, means on said outer frame engageable with said support members for suspending said outer frame from said support members, means on said outer frame for moving said outer frame upwardly relative to said first mentioned means to force said flanges against the underside of said ceiling and to hold said outer frame in said last mentioned position, said outer frame having a centrally disposed opening to provide access through said outer frame to space above said ceiling after installation of said fixture in said ceiling, and means integral with said outer frame for detachably pivotally securing a reflector thereto.
